(57) **CLAIM**

The ornamental design for a suspended light fixture, as shown and described.

DESCRIPTION

FIG. 1 is a perspective view for a suspended light fixture according to our new design.

FIG. 2 is a front plan view thereof.

FIG. 3 is a rear plan view thereof.

FIG. 4 is a right plan view thereof.

FIG. 5 is a left plan view thereof.

FIG. 6 is a top plan view thereof.

FIG. 7 is a bottom plan view thereof; and,

FIG. 8 is another perspective view thereof.

The broken lines shown in the drawings illustrate portions of the suspended light fixture that form no part of the claimed design.
